B. E. MEACHAM,
THERMO CONTROLLED GAS OVEN,
APPLICATION FILED FEB. 23, 1916.

Patented July 23, 1918.

2 SHEETS—SHEET 2.

UNITED STATES PATENT OFFICE.

BENJAMIN E. MEACHAM, OF LORAIN, OHIO, ASSIGNOR TO AMERICAN STOVE COMPANY, OF ST. LOUIS, MISSOURI, A CORPORATION OF NEW JERSEY.

THERMO-CONTROLLED GAS-OVEN.

1,273,644.

Specification of Letters Patent.

Patented July 23, 1918.

Application filed February 23, 1916. Serial No. 79,928.

To all whom it may concern:

Be it known that I, BENJAMIN E. MEACHAM, a citizen of the United States, residing at Lorain, in the county of Lorain

5 and State of Ohio, have invented certain new and useful Improvements in Thermo-Controlled Gas-Ovens, of which the following is a specification, reference being had therein to the accompanying drawing.

10 This invention relates to improvements in thermo-controlled gas-ovens, and the object of the invention is to so arrange and locate the parts of the thermo-regulating means as to immediately subject it to the influence 15 of a lowered temperature in the oven occasioned by the opening of the oven door, whereby an immediate and increased flow of gas is obtained to reestablish and maintain a uniform temperature throughout the oven 20 chamber.

25 This invention pertains to that class of gas ovens in which the heat within the oven is controlled by a thermo-actuated gas valve, for the purpose of maintaining a desired predetermined heat within the oven chamber, and the desired predetermined heat capable of being adjusted to suit the varying conditions of cooking different kinds of food.

30 In thermo-regulated ovens heretofore known to me, the thermo-regulating means is so located that there is a great lag in the effect thereof by reason of a cooling or lowering of the temperature in the oven due to 35 the opening of the oven door, and therefore a delay and lag in the increase of the gas flow by the thermo-regulated means to re-establish and maintain a uniform predetermined temperature within the oven chamber.

40 In thermo-actuated devices, there is a lag in their operation in response to either the rising or lowering of the temperature, because of the time required, in the first instance, to bring the temperature of the thermo-device up to the increased temperature, and due, in the second instance, to the time required to cool the thermo-regulated device in the lowering temperature, and this 45 may be aptly referred to as the lag in the operation of the thermo-actuated device. By reason of this fact, thermo-controlled gas-ovens heretofore known to me, have not quickly responded to the changes in the 50 temperature of the oven chamber, which I 55

have discovered is due largely, if not wholly, to the location of the thermo-actuated devices in the oven chamber.

I overcome this objection in thermo-controlled ovens, heretofore known to me, by 60 so placing the thermo-actuated member that it is within the zone of the cool portion of the oven caused by the opening of the oven door, and by reason of this, it is subjected to the cool air zone and, therefore, quickly 65 responds to the lowered temperature within the oven, and correspondingly quickly increases the flow of gas to reestablish and maintain a uniform pre-determined heat within the oven chamber.

70 That portion of the oven chamber which is at the oven door opening and is usually the front end of the oven chamber, is the coolest zone of the chamber, due to the opening of the oven door, and for the purposes 75 of this improvement will be referred to as the "cool zone" of the oven chamber. This portion of the oven chamber, I find to be the cool zone thereof when it is first being heated up in that it is the last part to become 80 heated to the predetermined temperature, due to the fact of a greater amount of metal at the door opening and to the fact that there is an opening at this point, which it is not practical to make absolutely air-tight, 85 and it is the cool zone of the oven chamber, when the oven door is opened to examine the food being cooked due, of course, to the fact that the cool air from the outside is greatest within the chamber immediately at 90 or adjacent the door opening.

95 My present improvement is to make the thermo-device immediately subject to the lowering of the temperature by the opening of the door, and to raise the cool part of the chamber when first heating up the oven, to the desired predetermined heat, by placing the thermo-actuated member within the oven just above the door opening, whereby it is 100 in the cool zone of the oven for the purpose of maintaining a uniform heat throughout the oven, and for the purpose of reestablishing a predetermined heat in the oven after it is cooled by the opening of the oven door.

105 I have discovered that when the temperature at the center of the oven and back of that point has been raised to the desired temperature, the front end of the oven, where there is the greatest amount of metal 110

and where the door-opening is located, will not be at the same temperature as the center and back portion of the oven, and the thermo-actuated member begins to cut off the 5 gas before there is a uniform predetermined temperature throughout the oven. I have also discovered that when the thermo-actuated device is located at about the center of the oven, or back of that point, the temperature at said point is not sufficiently lowered by the ordinary opening of the oven door to examine the food to bring the thermo-member quickly under the influence of the change of temperature and, therefore, 10 does not quickly respond to turn on the gas to quickly reestablish the desired predetermined temperature in the oven.

I have also discovered that by placing the thermo-actuated chamber in the front, or 20 door end of the oven, which is its cool zone, it will not begin to turn off the gas until the temperature throughout the chamber has been raised to the desired uniform degree, and it will quickly respond to a lowering of 25 the temperature due to the opening of the oven door and, therefore, quickly increase the flow of gas and quickly reestablish and maintain the desired predetermined temperature in the oven.

30 In the accompanying drawing:

Figure 1 is a perspective view of a gas oven constructed with my improvement.

Fig. 2 is a front elevation, partially in section.

35 Fig. 3 is a sectional view on the line 3—3 of Fig. 2, and also partially in section.

In carrying out my invention, the usual oven casing 1 is provided and this casing has at its front end the usual oven door 2.

40 Located in the bottom of the oven is the burner tube 3, communicating with any desired form of burner 4, which burner is only diagrammatically indicated by dotted lines. Located outside of the oven is a housing 5, 45 in which is located a thermo-actuated lever 6. The lower end of this lever 6 is operatively connected with a needle-valve 7, to control the amount of gas flowing into the burner mixing tube 3. Located at the upper 50 end of the housing 5 is a fulcrum 8 for the upper end of the lever 6 and a thermo-actuated member 9 engages the lever 6 between its fulcrum 8 and the gas valve 7. This thermo-actuated member or rod 9 is of the 55 well-known construction and is not here shown in detail and is not necessary for the understanding of my present improvement. As shown in Fig. 1, the housing 5 is located at the front edge of the oven and the thermo-actuated member 9 is in the front end of the oven, and as here shown, extends therein just above the door opening 10. The fulcrum 8 is adjustable for the purpose of regulating the device to be actuated at the 60 desired temperature by means of a suitable 65

hand wheel 11, and this hand wheel 11 is held at its adjusted position by means of a suitable latch 12. Since this forms no part of my present invention, further description here is unnecessary.

70 For the purpose of preventing the gas from being completely cut off by the action of the thermo-member 9, upon the lever 6, I provide a stop-screw 13, which will be set to let just enough gas flow to prevent the 75 burner from being completely or partially extinguished and thus letting the gas escape within the oven, or the burner "popping out" or "firing back", and this is one of the details of my present improvement which it 80 is desired to protect by this application.

As shown, the upper end of the housing 5 is in communication with the gas manifold 14, through the means of a branch pipe 15, in which is located a valve 16 for completely 85 cutting off the gas to the housing 5.

Owing to the location and arrangement of the thermo-actuated member here shown, it is located in the cool zone of the baking chamber when it is being first heated up to 90 prevent cutting off of the gas until the complete chamber is uniformly heated to the desired predetermined temperature, and it is so located that it is quickly influenced by the cool air entering the chamber when the 95 door is open and, therefore, quickly increasing the flow of gas to reestablish and maintain within the oven chamber the desired predetermined temperature, and it obviates the lag in the operation of the thermo-control heretofore existing, and it obviates the 100 lag in maintaining the desired predetermined uniform heat in the oven chamber in the constructions heretofore used so far as known to me.

105 Having thus described my invention, what I claim and desire to secure by Letters Patent is:

1. A gas stove having cooking burners, an oven, a housing communicating with the gas supply for the cooking burners, burners for the oven, the gas supply for the said oven burners communicating with the housing, a valve in said housing for controlling the said gas supply to the oven burners, and a 110 thermo-actuated member located in the cool zone of the oven and operatively associated with said valve for controlling it whereby the thermo-actuated member quickly responds to the change of temperature in the oven for the purpose of reestablishing and maintaining a desired predetermined temperature.

115 2. In a thermo-controlled gas oven, the combination with an oven, of a burner for 120 heating the oven, a fuel valve for the burner, a thermo-actuated member operatively connected with the fuel valve and extending across the oven in a direction parallel with the oven door opening and thereby wholly 125 130

located in the cool zone of the oven adjacent to the door opening to be quickly affected by the cooling of the oven to turn on the gas and quickly reestablish and maintain the 5 desired predetermined temperature within the oven chamber.

3. A gas stove having cooking burners, an oven, a housing communicating with the gas supply for the cooking burners, a burner 10 for the oven, the gas supply for the said burner communicating with the housing, a fuel valve for the oven burner, a thermo actuated member extending into the oven, a lever operatively connecting the thermo member with the fuel valve, and means for 15 limiting the closing movement of the lever and therefore the closing movement of the fuel valve for the purpose described.

4. A gas stove having cooking burners, an 20 oven, a housing communicating with the gas supply for the cooking burners, a burner for the oven, the gas supply for the said oven, the gas supply for the said burner

communicating with the housing, a lever within the housing, a fuel valve within the 25 housing and connected to one end of the said lever, a thermo-actuated member extending through the housing engaging the said lever and also extending into the cool zone of the oven for the purpose described.

5. A gas stove having cooking burners, an oven, a housing communicating with the gas supply for the cooking burners, burners for the oven, the gas supply for the said oven burners communicating with the housing, a 35 valve in said housing for controlling the said gas supply to the oven burners, and a thermo actuated member, extending within the oven and operatively associated with said valve for controlling it.

In testimony whereof I hereunto affix my signature in the presence of two witnesses.

BENJAMIN E. MEACHAM.
